(57) **CLAIM**

We claim the ornamental design for a kitchen cabinet with dishwasher, as shown and described.

DESCRIPTION

FIG. 1 is a perspective view of a kitchen cabinet with dishwasher showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view of a kitchen cabinet with dishwasher showing a state of the cover thereof opened;

FIG. 9 is a front elevation view thereof;

FIG. 10 is a rear elevation view thereof;

FIG. 11 is a left-side elevation view thereof;

FIG. 12 is a right-side elevation view thereof;

FIG. 13 is a top plan view thereof;

FIG. 14 is a bottom plan view thereof; and,

FIG. 15 is a perspective view in a disassembled state thereof.

The broken lines in the drawing figures are for purpose of illustrating an environment of use and form no part of the claimed design.

1 Claim, 15 Drawing Sheets
